UNITED STATES PATENT OFFICE.

ARTHUR M. LESLIE, OF CLEVELAND, OHIO.

DESIGN FOR A SEWING-MACHINE STAND.

SPECIFICATION forming part of Design No. 13,180, dated August 15, 1882.

Application filed January 12, 1882. Term of patent 14 years.

To all whom it may concern:

Be it known that I, ARTHUR M. LESLIE, a citizen of the United States, residing at Cleveland, in the State of Ohio, have invented and 5 produced a new and original Design for Sewing-Machine Stands, of which the following is a specification.

This design relates exclusively to the shape or configuration of the cast-iron work of a sewing-machine stand proper; and the principal distinguishing characteristic of the design as a whole is a pleasing combination and arrangement of angular outlines, which may be compared to those of a spider's web, the principal 15 members of all the parts being formed by straight lines, the effect being an airy lightness combined with the requisite stiffness and strength and freedom from projections upon which the clothing of the operator might catch.

20 Said design has been embodied in sewing-machines made under my inventions and patents, and known as the "Leslie sewing-machines," but may be used wholly or in part in the stands of other sewing-machines.

25 In the accompanying drawing the figure is a perspective view of a "No. 1" Leslie sewing-machine, illustrating this design as seen in use.

H represents the "head," or machine proper, with its hand-wheel and pulley and its attaching-hinges; and T represents the wooden table-top with its leaf and drawer, the former hanging down, none of which constitute any 30 part of the present design.

B represents the band-wheel; C, the central brace; E E, the end frames; G, the band-wheel guard, and Q the treadle, which constitute, with their connections, the "stand" of the machine.

The mechanical construction of this stand, 40 including particularly the means for hanging the band-wheel and supporting the band-wheel guard, is described and claimed in an application for patent of invention of even date herewith, and, together with the shape of 45 such parts as the pitman r and band d, forms no part of this design.

The band-wheel B has straight grooved arms and its rim is angular in cross-section, and the central brace, C, has straight or nearly straight 50 arms and an angular center, to render them harmonious elements of the design as a whole.

The two end frames, E, are made of one and

the same shape or configuration, which is clearly shown at the left-hand end of the stand in the drawing.

In the plane of the band-wheel B a circular center, 1, is formed with two concentric rings, 2 3, around the same, the inner ring being circular and the outer ring hexagonal, and four laterally-projecting radial struts, 4, unite the 60 said center and rings with each other and with two pairs of straight diverging edge-bars, 5 6, which extend upward and downward respectively therefrom. The upper edge-bars, 5, are connected with the customary top bar (concealed by the table-top) through the medium of a pair of bars, 7, which extend from said top bar downward and inward across the upper ends of said edge-bars to a vertical bar, 8, which unites the inner ring, 2, with said top 65 bar, while a like vertical bar, 9 9, extends downward from said inner ring to the lower transverse members, which consist of the customary sign-bars, 10, (which support between them block-letters forming the name of the 70 machine,) and a pair of converging bars, 11 11, extending inward and downward to the treadle-axis. Diverging feet 12 12, each terminating in a roller, project from said bars 11 and complete the shape or configuration of each end 75 frame.

The band-wheel guard G is segmental in general shape, having an imperforate beveled outer edge, 13, and two other ring-segments, 14 15, concentric with the band-wheel axis, 80 united by three radial ribs, 16. The shape of its attaching-foot, which projects from said outer edge, 13, is not considered material.

The treadle Q, so far as the present design is concerned, is a flat rectangular casting with 90 beveled corners, having a smooth edge, 17, immediately within which is an open-work border, 18 18, of angular figures. Within said outer edge and border the manufacturer's trade-name is formed by block-letters between parallel longitudinal bars 19 19, and the lettering-spaces are filled out at each end by leaf-shaped figures 20 20.

I claim as new—

1. The shape or configuration of the end frames, comprising a series of concentric rings in the plane of the band-wheel axis and an angular outer edge, substantially as shown.
2. The shape or configuration of the segment-

al band-wheel guard, with its imperforate bevelled outer edge, radial ribs, and concentric ring-segments, substantially as shown.

3. The shape or configuration of the treadle, with its open-work border of angular figures and its leaf-shaped figures to fill out the lettering-spaces, substantially as shown.

4. The shape or configuration of the stand as a whole, comprising the angular end frames,

wheel-guard, and treadle, with an angular central brace, the principal members of all the parts being formed by straight lines, combined and arranged as represented, as a new design for sewing-machine stands.

A. M. LESLIE.
